ATTACHMENT FOR THE HANDLE OF DRIVEN
TOOL-EQUIPPED FLEXIBLE SHAFTS

Paul A. Sigvathsen, Minneapolis, Minn.

Application October 23, 1950, Serial No. 191,540

3 Claims. (Cl. 144—134)

1

My invention relates to improvements in driven handle-equipped flexible shafts for operating various different kinds of tools in which the specific tool is manually held to its work.

The principal object of this invention is to provide a novel attachment applicable to the handle of a driven flexible shaft that is manually moved to feed a tool operated thereby to its work.

A further object of this invention is to provide such an attachment for positively guiding a tool to its work as said attachment is manually moved.

Other objects of this invention will be apparent from the following description, reference being had to the drawing.

While the attachment is intended for general use, in connection with a driven flexible shaft holding a tool for a specific use, it is especially well adapted for manually moving and mechanically guiding a tool designed to remove, by cutting, old putty from a window sash in preparing the same for reglazing.

To the above end, generally stated, the invention consists of the novel devices and combination of devices hereinafter described and defined in the claims.

In the accompanying drawing, which illustrates the invention, like characters indicate like parts throughout the several views.

Referring to the drawing:

Fig. 1 is an elevational view of an electric motor-driven flexible shaft, to the handle of which the attachment is applied, a portion of the flexible shaft being broken away;

Fig. 2 is a view of the attachment removed from the handle of the flexible shaft, partly in plan and partly in horizontal section taken on the line 2—2 of Fig. 1;

Fig. 3 is a front end elevational view of the attachment, as shown in Fig. 2; and

Fig. 4 is a fragmentary detail view partly in plan and partly in section taken on the line 4—4 of Fig. 1.

The numeral 5 indicates an electric motor on a mount 6 having an upstanding apertured ear 7 for hanging said mount from a support, not shown.

A flexible shaft 8 in a casing 8^a is attached at one end to the armature shaft 8^b of the motor 5 by a coupling 8^c. On the outer end of the flexible shaft 8 is a clutch 9 that holds a tool 10. A long sleeve-like handle 11 is turnably mounted on a sleeve bearing 11^a on the outer end portion of the casing 8^a. The tool 10 has spiral cutting edges 12 that extend longitudinally relative to the axis of said tool and is designed for cutting old putty to

2

remove the same from a sash. The parts thus far described are conventional except the tool 10.

Referring now in detail to the invention, wherein the numeral 13 indicates a base having parallel sides and a smooth bottom adapting the attachment to slidably rest on a piece of work such as a window sash: A handle 14 extends above and longitudinally of the base and is integral therewith. The base 13 has at its front end an upstanding member 15 that projects above the handle 14. The outer face of the base member 15, at its upper end portion, is flat, slightly outset, as indicated at 16, perpendicular to the bottom of the base 13 and extends at a right angle to the sides of said base. A hole 17 extends through the base member 15 from front to rear and its axis is parallel to the bottom of the base 13 and perpendicular to the surface 16.

A head 18 has flat contact with the surface 16 on the base extension 15 and is provided with a fixed screw stud 19 that extends through the hole 17 and supports the head 18 to turn about a horizontal axis. A wing-nut 20 is applied to the screw stud 19, impinges the back of the base extension 15 and frictionally clamps the head 18 onto said extension. In the front of the head 18 is a long semi-circular seat 21, the axis of which is perpendicular to the bottom of the base 13 when said head is positioned as shown in the drawing. A similar seat 22 is formed in the right-hand side of the head 18 and a like seat 23 is formed in the left-hand side of said head. Hinge lugs 24 are formed in the head 18 between the two seats 21 and 22 and similar lugs 25 are formed in the head 18 rearwardly of the seat 23. A pair of vertically spaced notches 26 are formed in the head 18 between the two seats 21 and 23 and a screw stud 27 having at one end an eye 28 extends into each notch 26 and is secured to the head 18 by a pin 29 that extends through aligned holes in the head 18 and the eyes 28. Formed in the head 18, rearwardly of the seat 22, is a pair of vertically spaced notches 30. A screw stud 31, having at one end an eye 32, extends into each notch 30 and is secured to the head 18 by a pin 33 that extends through aligned holes in said head and the eyes in the screw studs 31.

While the seats 21, 22 and 23 are shown perpendicular to the bottom of the base 13, they may be positioned obliquely to said bottom by turning the head 18 about the axis of the screw stud 19.

As shown, the attachment is secured to the handle 14 by placing said handle in the seat 21 and rigidly holding the same therein by a semi-circular clamping band 34 of substantially the same

length as the seats 21, 22 and 23. This clamping band 34 has on one of its longitudinal edges open hinge lugs 35 which fit between the hinge lugs 24 and are removably attached thereto by a fixed hinge pin 36. On the other longitudinal edge of the clamping band 34 is a flange 37 having therein a pair of notches 38 through which the screw studs 27 project. Spacing sleeves 29 and wing-nuts 40 are applied to the screw studs 27 and lock the clamping band 34 to the head 18.

To mount the handle 14 in the seat 22, the clamping band 34 is removed from the hinge pin 36, turned end for end and again interlocked with said hinge pin. In this position of the clamping band 34, it is secured to the head 18 by the screw studs 31.

To mount the handle 14 in the seat 23, the clamping band 34 is removed from the hinge pin 33, again turned end for end and held interlocked with the hinge lugs 25 by a fixed hinge pin 41 and secured by the screw studs 27 to the head 18.

The various seats 21, 22 and 23 permit different lateral adjustments of the tool 10 relative to the base 13. The tool 10 may be raised or lowered by vertically adjusting the handle 11 in the respective seats 21, 22 and 23.

A pair of guides 42 for the base 13 is provided. Each guide 42 is in the form of a rod 43, one end portion being bent laterally and a sleeve-like collar 44 mounted thereon. These rods 43 extend through transverse holes in the base 13 near each end portion thereof. Each rod 43 is held where adjusted relative to the base 13 by a set screw 45.

Obviously, the guides 42 may be endwise adjusted or turned to swing the rollers 44 about the axis of the rods 43, to position said rollers for engagement with an object to guide the same. With the rollers 44 in contact with an object to guide the base 13, the attachment may be manually slid on the object on which it rests to feed the tool 10 to its work.

The drawing illustrates a commercial form of the invention, but it will be understood that the same is capable of certain modifications as to details of construction, arrangement and combination of parts within the scope of the invention herein disclosed.

What I claim is:

1. A tool for removing old putty from a window

sash including a handle-equipped rectangular elongated base having a smooth flat bottom, means mounted on the base at one end thereof for vertical adjustment and having a driven member for holding a tool, and a round tool of a constant diameter held by the driven member with its longitudinal axis perpendicular to the bottom of the base, said tool having a spiral cutting edge, the lower end of the tool being flat and perpendicular to said axis.

2. The structure defined in claim 1, further including an independent guide at each end portion of the base, each guide including a long rod extending endwise through a transverse hole in the base, one end portion of each rod being bent laterally and having mounted thereon a sleeve-like member, and means for holding each rod where endwise adjusted relative to the base.

3. A base member having an elongated, rectangular flat bottom and a handle by means of which said base member may be slidably moved directly on a piece of work, said base member also having, at one end, an upright extension provided with an outer face that is perpendicular to the bottom of the base member, spaced thereabove and outwardly offset from said end of the base member, an outwardly projecting head attached to said outer face, said head having clamping means for holding the sleeve-like handle of a tool having a driven cutter extending below the last noted handle, a pair of laterally spaced guides for the base member, each including a rod extending endwise through a transverse hole in the base member, one end portion of each rod being turned downwardly, and means holding the rod in endwise adjustment.

PAUL A. SIGVATHSEN.
